UNITED STATES PATENT OFFICE.

JOHN N. THORNTON, OF JERSEY CITY, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMPUTING-MACHINE.

1,228,148.

Specification of Letters Patent. Patented May 29, 1917.

Application filed April 5, 1912. Serial No. 688,581.

To all whom it may concern:

Be it known that I, JOHN N. THORNTON, a citizen of the United States, residing in Jersey City, in the county of Hudson and 5 State of New Jersey, have invented certain new and useful Improvements in Computing-Machines, of which the following is a specification.

This invention relates to computing machines, of the kind disclosed in United States Patent to Hans Hanson, No. 905,421, dated December 1, 1908, and in the British Patent No. 3390 of 1912, in which computation pins are set up by the keys, and 10 then employed to drive the dial wheels, and in which a set of tens-carrying trains is operable by the general operator of the machine upon its return stroke, and is an improvement on an application of Frederick 15 A. Hart, No. 669,751, filed January 6, 1912.

The principal object of the present invention is to provide inexpensive, simple, reliable and durable means for preventing faulty action of the machine, due to liability of overthrow of the dial or computing wheels or the tens-carrying trains.

In the type of the machine shown in the patents referred to above, the computing wheels, when they have completed one cycle 30 of movement, set members of a tens-carrying train, which members are subsequently given a movement by the general operator for the purpose of carrying from lower to higher orders throughout the computing wheels. It has been heretofore proposed to have the general operator, at the completion of its initial stroke, call into action overthrow-preventing means, one for 35 each numeral wheel, to prevent overthrow thereof, and to have devices individual to each denomination for controlling the same overthrow-preventing means during the carrying operation. Such a construction is disclosed in the application of Frederick A. 40 Hart, No. 655,680, filed October 20, 1911.

It has also been proposed to provide means to prevent overthrow of the tens-carrying members which are preliminarily set when a numeral wheel completes its 45 cycle of movement. Such a construction is disclosed in the application of Frederick A. Hart, No. 669,751, filed January 6, 1912.

In the construction which I have illustrated, a stop or check is normally in position 50 to prevent overthrow of any member of the tens-carrying train which is to be

preliminarily set up by a dial or computing wheel, and said check is carried on the shaft which carries the spurs for completing the operation of the tens-carrying train; 60 and each of the spurs is provided with a dwell or locking edge which prevents overthrow of the tens-carrying train when the latter has been driven by a spur. These spurs operate the carry-over trains to rotate 65 the dial wheels each one point; and in order to prevent overthrow of the dial or computing wheels when operated by the carry-over trains, there is also preferably provided on said spur shaft, a series of cams, 70 which call into action devices for locking the dial wheels against overthrow; these preferably being the same locks that are employed at the conclusion of the forward stroke of the general operator, as above 75 explained.

The spurs are arranged helically along their shaft, so as to become effective one after another, and the aforesaid cams for locking the dial wheels have a corresponding helical arrangement, so that the dial wheel locks are actuated one after another at the proper points.

Other features and advantages will hereinafter appear.

In the accompanying drawings,

Figure 1 represents a diagrammatical sectional side view of a computing machine of the Underwood-Hanson type, showing the present invention applied thereto.

Fig. 2 is a plan view of the computing wheels and some allied parts.

Fig. 3 is a side view of the same in normal position.

Figs. 4, 5 and 6 show a computing wheel 95 and some associated parts in various positions of the carry-over mechanism.

Fig. 7 is a rear view of the computing wheels and some allied parts.

Fig. 8 is a view of a locking member for 100 a dial wheel.

Fig. 9 is a view of a locking and turning spur for a carry-over train.

Figs. 10 to 17 are views of locking and turning spurs for the various carry-over trains. 105

Numerals 1 of the typewriter depress levers 2 to vibrate bell cranks 3, to swing type bars 4 up to print against a platen 5, which is mounted on a carriage 6. The latter is driven by a spring-barrel 7, and 110 has a rack 8 meshing with a pinion 9, connected to escapement wheel 10, which is

controlled by dogs 11; said dogs operated by a universal bar 12, which is driven by heels 13 on the type bars.

Said keys 1 have stems 14 to depress arms 15 on rock shafts 16, forming parts of linkages 17, which are depressed by said keys to engage and depress computation pins 18, the latter suitably mounted on bars 19. These bars 19 are elevated through the instrumentalities of a dog 20 on the carriage 6, said dog engaging jacks 21 one after another, to depress the links 22 and vibrate levers 23, which engage linkages 24, to raise the rear ends of said bars 19 *seriatim*.

15 After the keys 1 have been depressed to print the desired number on the work sheet, the typist pulls forwardly a handle 25, which is provided upon a rock shaft 26, the latter extending across the machine, and 20 having at its ends segments 27, which mesh with idle pinions 28, meshing with opposite racks 29, which form parts of the general operator; said racks connected by cross bars 30, 31.

25 The forward movement of said handle 25 carries the general operator forward, and cross-bar 30 engages such pins 18 as have been depressed by the keys, and drives forward the bars 19 accordingly; said bars 30 having on their forward ends racks 32 to mesh with pinions 33, which are connected to dial or computing wheels, 34; the latter loosely mounted on an arbor 35.

Each dial wheel is provided with a tooth 36, which once in every revolution engages one of the teeth of pinion 37 to start the tens-carrying train, of which said pinion forms a part. This is done while the dial wheel 34 is moving from "9" to "0"; said 40 tooth 36 turning said pinion substantially one ninth of a revolution. Said pinion is held in position by a light spring detent 37.

Fast to said pinion 37 is a three toothed pinion 38 to mesh with a gear 39, fast on 45 the dial wheel 34 next higher in denomination. Each tens-carrying train has its pinion turned one-third of a revolution at each operation thereof. The operation of a tens-carrying pinion and its train, after it has 50 been started by the tooth 36 during the forward stroke of the general operator 29, is completed during the return stroke of said general operator by one of a set of spurs or segments of gears 40 fixed upon a 55 shaft 41. In Figs. 3, 4, 5, 6 and 9, the spur shown is the one for the fourth computing wheel counting from the right;—viz., the thousands wheel.

Said shaft 41 is driven from the rack 29 60 through an idle pinion 42 (Fig. 3) and a pinion 43 meshing therewith and riding upon said shaft 41. Pinion 43 has a clutch connection to said shaft so as to revolve idly during the forward stroke of the general operator but makes one single com-

plete revolution during the return stroke thereof. Said clutch comprises a ball 44 (Fig. 7) fitted in a pocket 45 in said shaft and pressed by a spring 46 into a recess 47 in said pinion, the ball connecting the pinion and shaft during the return stroke of the pinion but releasing the shaft during the initial stroke of the pinion.

The spurs 40 are placed in helical order along the shaft 41 so as to operate the tens-carrying trains *seriatim*, starting with the lowest denomination and proceeding to the highest. When any tens-carrying train is in its normal position, Fig. 3, it is inoperable by its spur 40, since the pinion 37 is mutilated; every third tooth being cut away at 48 to make a clearance for the spur 40. So long as the tens-carrying train remains in normal position, the shaft 41 may revolve idly with respect thereto; but when a train 50 is moved by its associated tooth 36 from the Fig. 3 position to the Fig. 4 position, one of the teeth 49 of the pinion moves into the path of its spur 40, and the latter, therefore, at the ensuing movement of the shaft 41, drives the tens-carrying train and advances the next higher dial wheel 34, as shown in Fig. 5, until the normal position of Fig. 3 is reached. The shaft 41 and all the spurs then complete their revolution of 95 normal position.

In order to prevent overthrow of the tens-carrying train when it is started by the tooth 36 on any dial or computing wheel, there is provided fast to shaft 41 a series of stop teeth or fingers 50, one for each carry-over train. Each of these fingers normally lies in the path of the teeth 49 on the associated pinion and is so placed that when this pinion is rotated by the tooth on the corresponding dial wheel it may turn under this impetus until the next higher tooth 49 strikes said finger but no farther.

Thus on the forward stroke of the general operator the carry-over trains are set, and on the return stroke the rotation of shaft 41 rotates the pinion 48 until, as shown in Fig. 6, a concentric portion 51 formed as an extension on the spur 40 temporarily locks the pinion against further rotation, and then continues its rotation until finger 50 is in position to intercept the teeth 49 on pinion 48. It will be seen that each segment or spur 40 with its extension 51 in addition to assisting the tens-carrying forms a fragmentary or temporary Geneva lock which prevents overthrow of the associated pinion 37 and positively positions one of the gaps formed between every two pairs of the teeth 49, so that the segment or spur 40 will be 125 free to rotate idly, subsequently, unless the pinion 37 has been again advanced by its associated dial or computing wheel 34.

At the conclusion of the forward stroke of the general operator, the dial wheels 34 are 130

positively arrested against overthrow by means of stops or locks 53, shown in the form of levers, which enter between teeth of the gear 39 on each dial wheel. These stops 53 are normally held in inoperative position by means of springs 54, and are moved to locking position by means of a cam 62 fast on the general operator, which raises a finger 61 of a lever 60 carrying at its other end a bail 58. This bail overlies arms 57 on said levers 53, and so swings the locking toes of all the levers against the dial wheels when the cam 62 rides under the finger 61, which occurs at the end of the forward 15 stroke of the general operator.

These stops 53 are also employed to lock the computing wheels against overthrow by the carry-over trains, and for this purpose a series of cams 65 is formed fast on the 20 spur-carrying shaft 41, which cams each strike a finger 64 on an extension 56 on each stop 53 and swing each stop against its dial wheel immediately after its carry-over train has been operated by its spur 40. Since 25 there is no carry-over train operating the units wheel, the cam 65 may be omitted for said wheel.

The arrangement of carry-over actions including cams 65, spurs 40, and stop fingers 30 50 for the computing wheels, is shown in Figs. 10 to 17; Fig. 10 being the one from units to tens wheel, Fig. 11 from tens to hundreds, etc.

Each stop or detent 53 prevents overthrow of its associated dial wheel when operated by a carry-over train.

The operation may be summed up as follows:

After numeral keys 1 have been depressed 40 and pins 18 have been set, handle 25 is swung to move the general operator forward, and the bar 30 of said general operator picks up the computation racks or bars as it successively strikes the pins in their 45 different positions on the various racks, and thereby rotates the computing wheels 34. As the general operator concludes its forward stroke, its cam member 62 raises the lever 60 against the tension of spring 66, and by means of bail 58 forces each stop or 50 detent 53 to engage its respective computing wheel and prevents overthrow thereof.

On the return stroke, the shaft 41 is rotated by the general operator. The springs 55 54 pull the stops 53 out of the dial wheels, and any carry-over trains which may have been set are turned by their spurs 40. Immediately after each spur has passed the point at which it operates, the stop, check or 60 detent 53 for the associated computing wheel is swung by its cam 65 to lock said wheel until the whole surface of said cam passes the end 64 of said stop.

It will be noted that the racks on the reciprocating pin frames are always in mesh with

the wheels 35 and the computing wheels 39, and in order that the computing wheels may always be driven in one direction, a one way clutch 67 having ten points of seizing is inserted between the wheel 33 and the computing wheel 34. Usually a detent, such as 52, has been depended upon not only to prevent backward turning of the computing wheels, but also for the purpose of preventing overthrow of the computing wheels 70 when turned by the actuating devices. This invention belongs to a class in which a separate detent, such as 53, is employed, which prevents overthrow of the wheels when moved by the actuating devices, and it becomes no longer necessary to have the spring 75 detent 52 of sufficient strength to prevent overthrow, but the spring thereof may be made comparatively weak, its function being, with the present construction, merely to 80 prevent backward turning of the computing wheels, thus making the operation of the parts easier and less noisy.

Variations may be resorted to within the scope of the invention, and portions of the 90 improvements may be used without others.

Having thus described my invention, I claim:

1. In a computing machine, the combination with computing wheels, of means for 95 rotating them, a lock for each wheel normally disengaged therefrom but positively moving to lock its wheel at the end movement of the means for rotating them, a carry-over train for operating each wheel 100 from the one below, and means for moving each lock on movement of each carry-over train to lock each computing wheel immediately each carry-over train has completed the movement of its computing wheel. 105

2. In a computing machine, the combination with computing wheels, of means for rotating them, a lock for each wheel normally idle but positively locking its wheel at the end movement of the means for 110 rotating them, a carry-over train for operating each wheel from the one below, a tooth on each computing wheel for setting its carry-over train, positive means for moving said train when set, and a lock for arresting 115 said carry-over train when it has been thus positively turned, said first-mentioned lock also locking each computing wheel when it is turned by the carry-over train driving it.

3. In a computing machine, the combination with computing wheels, of a carry-over train for turning each wheel by the one below, a tooth on each wheel for giving each carry-over train an initial turn, a stop limiting said turn, a spur for positively moving 120 said train to turn the computing wheel it operates, a lock to arrest said train when it is moved by said spur, and a lock for said computing wheel for arresting it as it is moved by the carry-over train. 125

4. In a computing machine, the combination with computing wheels, of a carry-over train for turning each wheel by the wheel below, but normally out of mesh with each, 5 a gear for positively turning each carry-over train, a tooth on each computing wheel for turning its carry-over train so that the gear for positively turning it will mesh with it, a stop arresting said train in said 10 meshing position, and a lock for arresting each computing wheel as it is turned by its carry-over wheel.
5. In a computing machine, the combination with a gang of computing wheels and 15 a gang of carry-over trains associated therewith, of a gear for positively driving each carry-over train to turn the computing wheel it drives, a tooth on each computing wheel for setting its carry-over train so that 20 said train will mesh with its driving gear, a stop on said gear for arresting said train in meshing position, and a lock on said gear for arresting said train when it is turned.
6. In a computing machine, the combination 25 with a gang of computing wheels and a gang of carry-over trains associated therewith, of a gear for positively driving each carry-over train to turn the computing wheel it drives, a tooth on each computing wheel for setting its carry-over train so that 30 said train will mesh with its driving gear, a tooth on said gear for arresting said train in meshing position, a lock on said gear for arresting said train when it is turned, and a lock for each computing wheel arresting 35 it when said positive driving gear turns.
7. In a computing machine, the combination 40 with a gang of computing wheels and a gang of carry-over trains associated therewith, of a shaft, a gear on said shaft for positively driving each carry-over train to turn the computing wheel it drives, a tooth on each computing wheel for setting its carry-over train so that 45 said train will mesh with its driving gear, a tooth on said gear for arresting said train in meshing position, a lock for arresting each computing wheel, and a cam on said shaft for operating said lock when said driving gear has turned.
- 50 8. A computing machine having computing devices, operating devices therefor, and carrying mechanism which is preliminarily set and subsequently operated to carry; and comprising in combination, an overthrowing stop-piece acting to prevent overthrow of the carrying mechanism during the preliminary setting thereof and also at the carrying operation.
- 55 9. In a computing machine, the combination 60 with settable members, of computing wheels, a reciprocating operator to carry into said wheels numerals represented by the members set, means for locking said computing wheels at the end of one stroke of said operator, carry-over trains arranged to be set to turn one computing wheel by the one below, a tooth on each computing wheel to set the carry-over train for the adjoining wheel, a spur for turning each carry-over train positively moved by the opposite stroke of said operator, and a tooth locking said carry-over train against overthrow, moved to inoperative position while said carry-over train is moved. 70
10. In a computing machine, the combination 75 with computing wheels and mechanism for turning them, of a carry-over train including gear teeth for each wheel, a positively driven shaft for successively operating said trains by their teeth, a lock on said shaft for each train to prevent its overthrow, and means on said shaft locking each computing wheel when it is turned by its train. 80
11. In a computing machine, the combination 85 with numeral wheels, of a lock for each numeral wheel and normally disengaged therefrom for preventing overthrow thereof, means for carrying numbers into said numeral wheels operating all of said locks simultaneously, and carry-over mechanism operating said locks successively. 90
12. The combination with a series of computing wheels, of a series of locks normally 95 in inoperative position, one individual to each of said computing wheels, shifting means universal to all said locks arranged to move the same from inoperative to operative position concomitantly, and shifting means individual to each of said locks 100 for moving the same from inoperative to operative position as individuals. 100
13. The combination with a computing wheel, of a reciprocating lock for said wheel normally disengaged therefrom, means separate from said lock for swinging said lock to effective engagement with said computing wheel solely for an instant corresponding to the termination of the movement of the associated computing wheel so as to arrest the computing wheel to prevent overthrow, and means for moving said lock after actuation to ineffective normal position. 110
14. The combination with a series of computing wheels normally disengaged therefrom, of a series of reciprocating locks for 115 said computing wheels, driving means separate from said locks for concomitantly rotating said computing wheels variable amounts, and shifting means for momentarily rendering said locks effective and then moving said locks to ineffective normal position relieving said computing wheels of the drag of said locks. 120
15. The combination with a computing 125 wheel, of a lock for said computing wheel, a carry-over mechanism for said computing wheel, means for running up a number on said computing wheel, and actuating means for said lock operating to momentarily shift 130

- 5 said lock to its effective position at the termination of a movement of said computing wheel and then moving said lock to an ineffective position, said actuating means being operable either from said carry-over mechanism or from said running-up means according to whether the movement of said computing wheel which it is desired to arrest was caused by the former or the latter.
- 10 16. The combination with a plurality of computing wheels, of a carry-over train for each computing wheel, means for setting the carry-over train of each computing wheel from its associated computing wheel, an overthrow-preventing lock for said carry-over train, a lock determining the inactive position of the carry-over train, and a temporary lock for arresting each computing wheel after an actuation by the associated carry-over train.
- 15 17. An assisting tens-carrying member having an arm with a gap therein forming a spur on one side and a locking extension on the other side, said locking extension being located to the rear with respect to the direction of movement of said spur, a cam having a definite relative position with respect to said spur, and a stop finger having a definite relative position with respect to said spur and said cam.
- 20 18. The combination with an assisting shaft, of a series of spurs spirally located on said shaft, a series of cams spirally located on said shaft and having a definite relative position with respect to said spurs, and a series of stop fingers, one for each of said cams and said spurs, located in alignment with each other.
- 25 19. A computing machine having computing devices, including dial wheels, operating devices therefor, and carrying mechanism which is preliminarily set and subsequently operated to carry; and comprising in combination, a member for preventing overthrow of the carrying mechanism during the preliminary setting thereof, and means controlled by said member on movement thereof preventing overthrow of the dial wheels during carrying.
- 30 20. The combination with a series of computing wheels, of actuating mechanism for said computing wheels, a delayed carry-over mechanism for said computing wheels, a single set of overthrow locks normally disengaged from said wheels, and means for moving said locks into engagement with said computing wheels at the termination of any movement thereof either by said actuating mechanism, or by said carry-over mechanism to prevent overthrow of said computing wheels.
- 35 21. The combination with a series of computing wheels, of a series of overthrow locks, one for each of said computing wheels, actuating mechanism for said computing wheels, tens-carrying mechanism for said computing wheels, a general operator for driving said actuating mechanism on its initial stroke, and driving said tens-carrying mechanism on its secondary stroke, shifting means for bringing said overthrow locks into play at the end of the initial stroke of said general operator and acting to disengage said overthrow locks at the beginning of the secondary stroke of said general operator, and means for bringing said locks into play individually during the secondary stroke of said general operator and subsequent to the carry-over action for each computing wheel, so as to prevent overthrow of said computing wheels by said tens-carrying mechanism.
- 40 22. The combination with a series of computing wheels, of tens-carrying mechanism for said computing wheels, acting successively from each lower to each higher denomination from lowest to highest, overthrow locks normally disengaged from said wheels, one for each thereof, and operating means for said locks coming into play successively from lowest to highest, so as to move said locks to engage said wheels just subsequent to each possible carry-over operation of said tens-carrying mechanism.
- 45 23. The combination with a series of computing wheels, of actuating mechanism for running up numbers in said computing wheels, carry-over mechanism for carrying between said computing wheels, and a single set of overthrow locks normally disengaged from said wheels, said locks being controlled by said actuating mechanism and said carry-over mechanism, so as to be moved by either into operative engagement with said wheels, in order to prevent overthrow of said computing wheels by either said actuating mechanism in running up numbers, or by said carry-over mechanism in carrying from one computing wheel to another.
- 50 24. A computing machine having computing devices, operating devices therefor, carrying mechanism which is preliminarily set and subsequently operated to carry, and a general operator for the computing devices; and comprising in combination, means acted on by the movement of said general operator for preventing overthrow of the computing devices during computation, a member for preventing overthrow of the carrying mechanism during the preliminary setting thereof, and means called into action on movement of said member and acting on said overthrow preventing means for preventing overthrow of the computing devices at the carrying operation.
- 55 25. The combination with a series of computing wheels, of driving mechanism for running up numbers on said computing wheels, and overthrow locking mechanism

- momentarily engaged by said driving mechanism and engaging said computing wheels to prevent overthrow of said computing wheels by said driving mechanism, and instantaneously disengaging from both said computing wheels and said driving mechanism to render said computing wheels free for subsequent action, and itself free for subsequent action.
- 10 26. A carry-over mechanism comprising a series of driving spurs, a series of stop fingers having a definite relative position with respect to said driving spurs, and a series of cams, one for each spur, having a definite relative position with respect to said driving spurs.
- 20 27. A computing machine having computing devices, operating devices therefor, and carrying mechanism which is preliminarily set and subsequently operated to carry; and comprising in combination, an overthrow-stop-piece which in normal position acts to prevent overthrow of the carrying mechanism during the preliminary setting thereof, and when moved acts to prevent overthrow at the carrying operation.
- 30 28. A computing machine having computing devices, operating devices therefor, and carrying mechanism which is preliminarily set and subsequently operated to carry; and comprising in combination, a single stop-piece, said piece being provided with means for preventing overthrow of the carrying mechanism during the preliminary setting thereof, means for operating the carrying mechanism when set, and means for preventing overthrow of the carrying mechanism at the carrying operation.
- 40 29. A computing machine having computing devices, operating devices therefor, and carrying mechanism which is preliminarily set and subsequently operated to carry; and comprising in combination, a control device operating as a single piece, said device controlling the carrying mechanism during the preliminary setting thereof to prevent overthrow, the operation of the carrying mechanism when set, the overthrow of the carrying mechanism at the carrying operation, and the overthrow of the computing devices at the carrying operation.
- 50 30. A computing machine having computing devices, operating devices therefor, and carrying mechanism which is preliminarily set and subsequently operated to carry; and comprising in combination, a rotatable tappet piece, and means under control of said piece during a single rotation thereof for preventing overthrow of the carrying mechanism during the preliminary setting thereof, the operation of the carrying mechanism when set, the overthrow of the carrying mechanism at the carrying operation, and the overthrow of the computing devices at the carrying operation.
- 55 31. In a computing machine, the combination of a gang of computing wheels and a gang of carry-over trains associated therewith, a shaft, a gear on said shaft for positively driving each carry-over train to turn the computing wheel it drives, a tooth on each computing wheel for setting its carry-over train, so that said train will mesh with its driving gear, and a tooth on said shaft for preventing overthrow of said train when moved by said tooth on said computing wheel.
- 60 32. In a computing machine, the combination with computing wheels, of a general operator to carry numbers into said computing wheels, carry-over trains arranged to be set to turn one computing wheel by the one below, means on each computing wheel to set the carry-over train for the adjoining wheel, means for turning each carry-over train on movement of the general operator, and a rotatable tooth locking each carry-over train against overthrow during the setting thereof by the computing wheels.
- 65 33. In a computing machine, the combination with computing wheels, of a reciprocating operator to carry numbers into said computing wheels, means for locking said wheels at the end of one stroke of said operator, carry-over trains arranged to be set to turn one computing wheel by the one below, a tooth on each computing wheel to set the carry-over train for the adjoining wheel, a spur for turning each carry-over train moved by the opposite stroke of the reciprocating operator, and a rotatable tooth locking said carry-over train against overthrow during the setting thereof by the computing wheels, said locking tooth being moved to an inoperative position by its rotation.
- 70 34. In a computing machine, the combination with computing wheels, and carry-over trains having gear teeth for each wheel, of a shaft for successively operating said trains by their gear teeth, locking means on said shaft for each train to prevent its overthrow during preliminary setting and during carrying, and means on said shaft acting to prevent overthrow of each computing wheel when it is turned by its train.
